Mich., a corporation of Michigan

Application September 16, 1947, Serial No. 774,194

4 Claims. (Cl. 214—1)

1

The present invention relates to a material handling system which is particularly but not exclusively adapted for receiving newly molded concrete building blocks from a block-making machine and for conveying the blocks to storage or treating kilns.

Among the objects of the present invention are to provide an improved material handling system which is particularly but not exclusively adapted for use with brick or concrete block-making equipment wherein bricks, concrete blocks, and the like are manufactured by continuous mass production methods involving a continuous flow of material from the raw material stockpiles, through the mixing apparatus, the block-molding machine, and to the final block curing kilns and storage yards; and in particular to provide such a material handling system wherein the newly formed blocks or the like are economically and speedily conveyed from the block-making machine to the curing kilns and/or storage yards by automatic and semi-automatic processes and with the minimum of handling.

Another object of the present invention is to provide an improved continuously operative conveying system wherein an empty tram conveyor is automatically loaded at a loading position with blocks from a block-making machine and conveyed therefrom along tram rails, being automatically replaced at the loading position by another empty tram conveyor.

Another object is to provide an improved conveyor system of the character described wherein the tram conveyor provides a plurality of block-receiving shelves arranged in vertical tiers, the empty tram conveyor being conveyed along tram rails to an automatically operated conveyor handling mechanism which maneuvers the tram conveyor to a block loading position adjacent a block-making machine, whereat said shelves are successively loaded automatically with newly-formed blocks, the block loading tram conveyor being then automatically hoisted to an elevated end of an inclined tram rail along which the tram conveyor rides to said curing kilns and/or storage yards.

Other objects of this invention will appear in the following description and appended claims, reference being had to the accompanying drawings forming a part of this specification wherein

like reference characters designate corresponding parts in the several views.

In the drawings:

Fig. 1 is essentially a schematic side view, partially in section and with portions broken away, showing a material handling system employing the present invention.

Fig. 2 is essentially a schematic plan view of the system shown in Fig. 1, showing also a portion of the tracks leading to the storage yards.

Fig. 3 is a fragmentary enlarged bottom view showing the conveyor at the loading position and being taken in the direction of the arrows essentially along the line 3—3 of Fig. 1, the supporting structure for the block loading conveyor belt being removed.

Fig. 4 is an enlarged side view of the conveyor in the block loading position within the conveyor handling frame, taken substantially along the line 4—4 in the direction of the arrows of Fig. 2, the block loading conveyor belt and the discharge tram rail being removed.

Fig. 5 is essentially an enlarged fragmentary end view of the lower portion of the conveyor and conveyor handling frame taken from the left end of Fig. 4.

Fig. 6 is essentially an enlarged fragmentary end view of the upper portion of the conveyor and conveyor handling frame taken from the left end of Fig. 4, portions of the hoist mechanism being broken away and sectioned to show details of construction, and portions of one of the hoisting shafts being broken away to show sectional details of the hoist control shaft, the traversing motor and support therefore being removed.

Fig. 7 is essentially an enlarged fragmentary top view of the right hand portion of the conveyor and conveyor handling frame shown in Fig. 4, the pneumatic cylinder and push-off mechanism being removed.

Fig. 8 is essentially an enlarged fragmentary top view of the left hand portion of the conveyor and conveyor handling frame shown in Fig. 4, the conveyor being shown in phantom in the initial entering position.

Fig. 9 is a schematic plan of electrical circuits suitable for use with the present invention.

Before explaining the present invention in detail, it is to be understood that the invention is not limited in its application to the details of

construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Section I.—General

In brief, the present invention provides an automatic conveyor means whereby newly formed building blocks may be received directly from a block molding machine and conveyed to treating kilns or storage. To this end, a number of tram carriers or conveyors, each having a plurality of block carrying shelves arranged one above another for receiving the newly formed blocks from the block-molding machine, are provided for riding along a tram rail between a conveyor handling frame and the said storage or treating kilns. The conveyor handling frame provides a mechanism for maneuvering each conveyor in turn to a loading position adjacent the block-molding machine.

Thus an empty conveyor returning from the storage or treating kilns rides along a return tram rail to its entering position within the conveyor handling frame, from whence a traversing mechanism provided by the handling frame automatically moves the conveyor to its loading position within the handling frame whereat the conveyor is then automatically loaded with blocks from the block-molding machine. The conveyor handling frame supports the carrier in its proper loading position during the loading operation and also provides a hoist mechanism for automatically raising the conveyor successively through vertical increments equal to the spacing between the said conveyor shelves as each shelf is loaded, permitting selective vertical alignment of each shelf in its turn at the proper level to receive the newly-formed blocks on their pallets from a chain conveyor, directly as they are stripped from the block-making machine.

The fully loaded conveyor is then hoisted by the handling frame to an elevated position of an outgoing tram rail from whence it runs by gravity along the tram rail to the storage or treating kilns. An empty conveyor returned by the return tram rail from the storage or treating kilns is then automatically received by the handling frame and the above outlined process is repeated.

Figs. 1 and 2 show a schematic plant layout for manufacturing building units, such as concrete blocks, and employing a particular arrangement by way of example of a conveyor system embodying the present invention. Letters of the alphabet are utilized primarily to indicate generally the major features of the conveyor system disclosed herein, which usually comprise a multiplicity of parts and details indicated by numerals.

The tram conveyor handling frame A is shown with a tram conveyor B in the loading position adjacent the concrete blocking-molding machine C. The block-molding machine C may be any one of numerous conventional block-making machines, although the present invention operates particularly successfully with the block-molding machine described in my co-pending application bearing Serial No. 688,118, now Patent No. 2,598,254.

Aggregate from the pit D is conveyed by the continuous bucket elevator E to the receiving hopper F where water and cement are added in

proper proportions and fed by gravity to the mixer G. The block-molding mix is delivered from the mixer G to the block-molding machine C, which operates on the mix and discharges the molded blocks H to the horizontal conveyor belt I, Fig. 3, while the blocks H still rest their pallets.

The conveyor B provides the plurality of horizontal shelves J, Figs. 1, 3, and 4, comprised of horizontal, longitudinally extending, paired T-beams arranged one above another in tiers along opposite sides of the conveyor B and having shelf portions 25, Fig. 5, which extend inwardly from opposite sides of the conveyor B. The conveyor chain I extends within the open front end of the conveyor B, slightly above the uppermost horizontal shelf J when the conveyor B is in its initial loading position, Fig. 1. The ends of the molded blocks H on the conveyor chain I overhang the sides thereof, Fig. 3, and also overlie the shelf portions 25 as shown by the phantom view of the block H in Fig. 5.

The blocks H are preferably discharged to the conveyor chain I from the machine C and advanced into the framework of the conveyor B on the conveyor chain I one by one as they are molded. When the chain conveyor I is completely loaded so that blocks H overlie the inwardly extending shelf portions 25 along essentially the entire length of the top shelf J, the conveyor B is automatically hoisted through a vertical increment equal to the vertical spacing between the shelves J. The blocks H are thus unloaded from the chain conveyor I to the top shelf J, and the second shelf J from the top is elevated to the position immediately below the chain conveyor I formerly occupied by the top shelf J, so as to receive the next load of blocks H from the chain conveyor I upon the next automatic increment of hoisting of the conveyor B. Finally when each shelf J is loaded, the loaded conveyor B is raised to the upper portion of the handling frame A and is pushed off onto the upper portion of the inclined track K.

The loaded conveyor B rolls by gravity down the inclined track K to the paired transverse rails L provided for the one or more bridge cranes M. Each bridge crane M provides a short bridge-track section, which may be aligned with the lower end of the track K to receive a loaded conveyor B therefrom, and which travels on its tracks L transversely to the tracks K and N to selectively align its bridge-track section with one of the parallel track portions N. The tracks N pass through the steam treating kilns O and lead to the paired transverse tracks P for the bridge cranes Q, which latter are similar in operation and function to the bridge cranes M and provide means for transferring the loaded conveyors B as they emerge from the steam kilns O, to one of the parallel tracks R which leads to the storage yards, and for transferring the empty conveyors B, as they return from the storage yards, to the empty-conveyor return tracks S. The empty conveyors B are then transferred by the bridge cranes M from the tracks S to the return track T, along which they are carried by the power driven belt means U to a walking beam escapement mechanism V adjacent the receiving side of the conveyor handling frame A.

The escapement mechanism V holds all the empty conveyors B as they are returned from the storage yards and dispenses them in their order of arrival one at a time as required into the handling frame A.

At the proper time when the handling frame A is in readiness to receive another empty conveyor B, the automatic escapement mechanism V is actuated to release the foremost empty conveyor B, which then rolls into the receiving portion of the frame A and is automatically moved by a traversing mechanism provided thereby to the lower forward loading position, Figs. 1, 2, and 4. Thus a complete cycle in the operation of a conveyor B, from the loading position adjacent the molding machine C, through the curing kilns O, to storage R, back to the loading position at the handling frame A, is completed.

Section II.—The block conveyor

Details of a particular embodiment of a conveyor B embodying the present invention are shown by way of example in Figs. 3, 4, and 5. The empty conveyor B enters the handling frame A at the rear and lower left thereof by way of the track T, Figs. 4 and 5, and is then maneuvered by a traversing mechanism provided by frame A to an initial loading position at which it is shown, lower right, Fig. 4. The frame A holds the conveyor B in the loading position until the latter is fully loaded. The loaded conveyor B is then elevated by a hoist mechanism also provided by the frame A to an exit position, upper right, Fig. 4, from whence the loaded conveyor B leaves the frame A by way of the tram rail K as above outlined.

The conveyor B is shown supported by two pairs of tram wheels 26 on the section of track 27 which is provided by the hoist mechanism of the frame A. The four wheels 26 are paired at opposite sides of the top portion of the conveyor B, each pair of wheels 26 being journaled in one of a pair of wheel supporting forks 28, which latter are secured to the transverse beam 29 near its opposite ends. The beam 29 is also secured at opposite ends to the pair of parallel beams 32, which in turn are secured to the top structure of the conveyor B along its opposite sides. The body of the conveyor B comprises an essentially rectangular frame structure preferably of angle and channel beams and having two parallel vertical sides formed from six upright supporting beams 33 distributed at the upright corner edges and at essentially the midportions of the two broader sides, Figs. 4 and 5. The two upper horizontal corner edges comprise the beams 34 joined at opposite ends to the corner uprights 33.

The aforesaid shelves J comprise the five pairs of horizontal T-beams secured to the uprights 33 within the interior broader sides of the conveyor B and having the inwardly extending shelf portions 25 which are conveniently spaced vertically to provide room for a horizontal row of blocks H on each shelf J.

At the back of the conveyor B, Fig. 4, are two horizontal cross braces 35 disposed between the back uprights 33. The corresponding space at the front or block receiving end of the conveyor B is unobstructed to permit entry of the conveyor chain I. Likewise the bottom of the conveyor B is also open to permit the hoisting of the latter above the chain conveyor I. Where required for additional reinforcement, the conveyor B provides a plurality of horizontal and vertical reinforcing plates 36 at the various junctures of the above mentioned beams and braces.

Section III.—The conveyor handling frame

Details of a particular embodiment of the conveyor handling frame A are shown by way of example in Figs. 4 through 8 wherein a steel trestle work is shown for supporting the automatic mechanism for handling the block carrying conveyor B. Three upright load supporting beams 41, 42, and 43 are located along the conveyor entering side of the frame A, left side, Figs. 5 and 6, and are positioned at the right edge, central portion, and left edge, respectively, as seen in Figs. 7 and 8. The upright beams 41, 42, and 43 rest upon supporting footings 44, are joined near their bases by the longitudinal horizontal reinforcing beam 45, and are joined and supported at their upper ends by the longitudinal horizontal reinforcing beam 46.

Three upright load supporting beams 47, 48, and 49 are positioned along the right edge, central portion, and left edge, respectively, Fig. 4, of the broad side of the frame A opposite the conveyor receiving side. The upright beams 47, 48, and 49 also rest upon footings 44, and are joined near their bases and near their upper portions by the longitudinal horizontal channel beams 51 and 52, respectively.

Horizontal transverse beams 53 and 54 are disposed between and secured at opposite ends to the upright beams 41 and 47 to comprise lower and upper transverse braces, respectively, for the block loading end of the frame A. Similarly, lower and upper transverse braces 55 and 56, respectively, are disposed between the upright supports 43 and 49 at the opposite end of the frame A.

The end of the frame A opposite the block loading end, Figs. 5 and 6, is braced by the crossing struts 57 which are secured at their opposite ends by screw-threaded attachments to the uprights 43 and 49 and are adjustable for tension by the turn buckles 58. The opposite or block loading end of the frame A is similarly braced at its upper portion by the adjustable tension struts 59, but the lower portion thereof is open to permit entry of the conveyor chain I and loading of the conveyor B with blocks H.

Opposite the conveyor entering side of the frame A and slightly below the top of the conveyor B when the latter is in its initial loading position within the frame A, Fig. 4, is the longitudinal and horizontal channel beam 62 which extends from an attachment at one end with the upright beam 49 to an attachment at the other end with the upright beam 41, being also secured at approximately its midpoint to the upright beam 48. On the conveyor entering side of the frame A and at approximately the same level as the beam 62 is a similar horizontal channel beam 61 which extends between attachments at opposite ends to the upright channel beams 41 and 42, and accordingly does not extend horizontally across the entire length of the frame A. An empty incoming conveyor B may thus enter the frame A between the upright beams 42 and 43 and along the tram rail T, which is supported from the horizontal beam 63, the latter being elevated above the horizontal beam 62 and being supported at opposite ends by attachments with the uprights 42 and 43. The various junctures between the horizontal and vertical supports of the frame A are suitably reinforced as required by the plurality of vertical and horizontal plates 64.

The rail portion 27, which supports the conveyor B and maneuvers the latter through its vari-

ous positions within the frame A, is rigidly secured to the lower ends of the two threaded hoisting shafts 66 by the two collar and nut assemblies 67, Fig. 6. The hoisting shafts 66 are depended from the traversing carriage indicated generally by the letter W for riding therewith and are raised or lowered by operation of the hoist motor 69, Figs. 6 and 7.

By operation of the traversing motor 65 and the sprocket chain 74 coupled between the motor 65 and the carriage W, the latter is pulled along the rails 72 and 73, Figs. 7 and 8. By cooperable action between the traversing motor 65 and the hoist motor 69, the track portion 27 and a conveyor B suspended therefrom may be raised or lowered or traversed essentially from one end of the frame A to the other. The traversing motor 65 is mounted on the platform 75 which is supported across and secured to the horizontal beams 56 and 76 by the plurality of bolts 77. The beam 76, Fig. 8, extends parallel to the beam 56 and is secured at opposite ends to the horizontal beams 52 and 46.

Across the top of the frame A at the right, Fig. 7, is the horizontal beam 78 which is supported at its opposite ends by the beams 46 and 52 in parallelism with and essentially at the same level as the transverse horizontal beam 54. The level platform 79 for the pulley mounting 82, which latter provides the bearing 83 for the axle shaft 84 of the driven pulley sprocket 85, is supported across the beams 78 and 54. The sprocket chain 74 is looped around the sprockets 85 and 87 and completes a continuous loop with the carriage W to which the chain 74 is secured at its opposite ends by the two tension adjusting bolts 86. The driving sprocket 87 is mounted on the motor driven shaft 88 for rotation therewith, the latter being driven by the reversible electric motor 65 to drive the sprocket chain 74 and to pull the carriage W in one direction or another along the rails 72 and 73.

The rail 72 is essentially square in cross section and stands on one edge to provide an inverted V-rail for interlocking with the two V-type carriage wheels 89 on the left side of the carriage W, Fig. 6, thus preventing accidental lateral movement of the carriage W from its tracks. The rail 72 is secured at its opposite ends by bolts 92 to the right angle brackets 93 which rest on and are secured to the cross beams 76 and 78 by the plurality of bolts 94.

The rail 73 provides a conventional flat rail surface for the two cylindrical carriage wheels 96 at the right side of the carriage W, Fig. 6, and preferably comprises a channel beam supported at opposite ends by the transverse beams 76 and 78 to which it is secured by the plurality of bolts 95. The wheels 89 and 96 are journaled to the ends of the two axle shafts 97 which are supported at their opposite ends within the rectangular frame 98. The frame 98 comprises the body of the carriage W and is reinforced at its corner portions by the plurality of flat reinforcing plates 99. A platform 102 is supported across and secured to the frame 98 by the bolts 103 and supports the mounting 104 for the hoist mechanism, including the hoist motor 69, the gear reducer 105, and the hoisting shafts 66. The mounting 104 is secured to the platform 102 by the plurality of bolts 101.

The hoist motor 69 is preferably a conventional reversible electric motor operatively coupled to the tubular shaft 106 for rotation thereof by means of the speed reducer 105. Shaft 106 is

5 journaled in the bearings 107 within the mounting 104 and is keyed to the central gear 108 which drives the pair of lateral gears 109. Each gear 109 is keyed to one of each of the two internal screw-threaded bushings 112 which is 10 journaled in the respective bearing 113 provided therefor by the mounting 104 and which is in screw driving engagement with one of each of the two screw-threaded hoisting shafts 66. In Fig. 6, the mounting 104 is broken away to show sectional details of the operable coupling between the shaft 106 and the right hoist shaft 66. It is to be understood that essentially the same coupling is also provided for the left shaft 66.

15 Upon rotation of the shaft 106 by the hoisting motor 69, the internally threaded bushings 112 are rotated to raise or lower the threaded hoisting shafts 66 in accordance with the direction of rotation of the hoist motor 69. Each internally threaded bushing 112 and its corresponding gear 109 keyed therewith is held against vertical movement by the flange 114 of the bearing 113 which fits against the depending shelf or shoulder 115 of the mounting 104.

20 A vertical hoist control shaft 116, Figs. 4 and 6, is secured at its upper end to the platform 102 by the plurality of bolts 117, Fig. 7, and extends downward to an attachment with the bracket 118 provided by the lower portion of one of the hoisting shafts 66. In Fig. 6, the left hand hoist shaft 66 which provides the bracket 118 is directly in front of the shaft 116 and is shown partially broken away to display sectional details of the hoist control mechanism provided by the shaft 116.

25 The hoist control shaft 116 provides four inclined slots 119, being one less in number than the number of shelves J provided by the conveyor B. Within each slot 119 is the pivotally mounted dog 122 which pivots on the pivot pin 123 secured within the shaft 116. The slots 119 are vertically spaced in accordance with the vertical spacing of the shelves J. Beneath the lowermost dog 122 and spaced therefrom by the vertical distance between the shelves J is the projection 124 of the hoist control shaft 116.

30 When each dog 122 rests on the inclined base of its corresponding slot 119 at the lower limit of its downward pivotal movement, it projects slightly from its slot 119. The slots 119 are adapted in size to permit upward pivoting of the dog 122 sufficiently to withdraw the projections thereof into slots 119. By operation described in more detail below, the dogs 122 and the projection 124 cooperate with a set of limit switches in an electrical control system to effect the automatic hoisting operations briefly outlined above.

35 Along the right side of the frame A, Fig. 5, and at the lower left portions thereof, Fig. 4, are a pair of horizontal bumpers 125 which are supported by a plurality of flexible and resilient mountings. The mountings for the upper and lower bumpers 125 are essentially similar but inverted with respect to each other.

40 Each bumper mounting includes an angle bracket 127, which is secured to its respective bumper 125 and is also secured to a pivot arm 128, the latter being pivotally mounted at 129 to a pivot bracket 132. The pivot brackets 132 for the upper and lower bumpers are secured to the horizontal beams 62 and 51, respectively, and are reinforced by webs 134 and 135. Projecting spring pilots 136 are provided by the brackets 127 and 133 for the coil springs 137 which provide a resilient backing for the bumpers.

125. A bumper movement limiting arm 138 is pivotally secured at 139 to each pivot arm 128 and is extended through an opening provided therefor in the corresponding bracket 133. The shoulder 142 of each arm 138 limits movement of the bumpers 125 against the tension of the springs 137 by contact with the brackets 133. Adjustment of the position of the bumpers 125 is permitted by the adjusting nuts 143 which are screw-threaded on the ends of the arms 138 projected through the brackets 133. As the empty conveyor B returned from the storage yards is released from the tramrail T into the hoist frame A by the automatic walking beam escapement mechanism V, the impact of the conveyor B is absorbed by the resiliently mounted bumpers 125.

When the conveyor B comes to rest within the frame A at its entering position on the track portion 27, the carriage W is then automatically moved to the loading position at the right, Fig. 4. A pair of horizontal guide bars 144, on opposite sides of the conveyor B and supported by the frame A, accurately guide the conveyor B to its loading position. The ends 145 of the guide bars 144 are flared outwardly to receive the conveyor B as it is moved by the traversing motor 65 from the entering position to the loading position.

Each bar 144 is supported by a plurality of supporting structures, four in the present example, comprising the laterally adjustable screw-threaded rods 146 and the webbed brackets 147. The brackets 147 which support the guide bar 144 along the left side of the conveyor B, Fig. 5, are secured to and supported by the horizontal beam 61. The corresponding brackets 147 on the other side of conveyor B are secured to and supported by the horizontal beam 62. Each threaded rod 146 is adjustably secured by the double adjusting nuts 148 to an upright boss 149 provided by the bracket 147, permitting lateral adjustment of the spacing between the guide bars 144.

Section IV.—Limit switches

The automatic operation of the present invention is effected by an electrical control circuit, Fig. 9, which is controlled by the opening and closing of a system of limit switches in accordance with the operation of the above described apparatus. As the empty incoming conveyor B rides on the track portion 27 of the hoisting mechanism and comes to rest against the bumpers 125, the cross beam 29 of the conveyor B strikes the normally open limit switch 151 which is supported from the horizontal beam 62 by the bracket 152, Fig. 5. The closing of limit switch 151 energizes the traversing motor 65 to drive the carriage W and the conveyor B supported therefrom on the track 27 to the loading position at the right in Fig. 4.

The limit of the travel of the conveyor B to the right is determined by the limit switch 153, Fig. 7, which is supported from the rail 73 by the bracket 154 and is tripped by the frame 98 of the carriage W when conveyor B reaches its loading position.

As the molded blocks H progress one by one toward the leftward extremity of the conveyor chain I, the foremost block H finally trips the limit switch 155, mounted upon the end of the support for the conveyor chain I, Fig. 3, and the hoist motor 69 is operated to raise the conveyor B and thereby to unload the blocks H from the

conveyor chain I to the upper shelf J. The hoist motor 69 stops when the uppermost projecting dog 122 trips the limit switch 156, Fig. 6, supported from the mounting 104.

5 The above outlined hoisting and shelf loading procedure is repeated four more times, loading each shelf J in turn. On the last hoisting operation, the conveyor B is raised until the track portion 27 aligns with the upper portion of the inclined tram rail K which is supported from the beam 52. In this position of the hoisting mechanism, both limit switches 156 and 157 are tripped by the projection 124, Fig. 6, and the hoist motor 69 again stops. Tripping of limit switch 157, secured to the mounting 104, energizes an electrically controlled air valve, not shown, which actuates the pneumatic ram 158, Fig. 6. The pneumatic ram 158 is supported by the beam 159, which extends across the top portion of the frame A and is supported at one end from the horizontal beam 52 by the bracket 162. The other end of the beam 159 is supported from the horizontal beam 46 by the bracket 163.

20 The pneumatic ram 158 provides the plunger rod 164 which is secured to the right end, Fig. 4, of the arcuate arm 165. The left end of the arm 165 provides the push-off rod 166 which extends through and is slidably mounted within an opening 167 provided therefor within the said left end of the arm 165. The right end of the push-off rod 166 in Fig. 6 is in alignment with and adjacent the conveyor beam 29, when the track 27 is at its elevated position in alignment with the track K, and provides the spring retaining flanged head 168 for the coil spring 169. The spring 169 is compressed between the flanged head 168 and the arm 165 to resiliently hold the push-off rod 166 to the right in Fig. 6 and to absorb the shock of impact when the conveyor B is pushed from the hoisting frame A upon actuation of the ram 158. The opposite end of the rod 166 extends from the other end of the opening 167 and is threaded to receive the retaining nuts 172 which hold the rod 166 in place 30 within the opening 167 against the force of the spring 169.

25 Upon tripping limit switch 157 and actuating hydraulic ram 158, the plunger arm 164 forces the flanged head 168 against the adjacent end of beam 29, pushing the loaded conveyor B on the track K along which it rides by gravity to the treating kilns as previously described. The limit of the stroke of the plunger arm 164 is determined by the limit switch 173, which is supported from the beam 159 by the bracket 174 and which is tripped by the arm 165 as the latter moves to the right, Fig. 6. The tripping of limit switch 173 de-energizes the above mentioned electrically controlled valve for the pneumatic ram 158, causing retraction of plunger 164.

35 The tripping of limit switch 173 also energizes the traversing motor 65 to move the carriage W to the left in Figs. 7 and 8. At approximately the midpoint of the leftward movement of the carriage W, limit switch 175, supported from the rail 73 by the bracket 176, Figs. 4 and 6, is tripped by contact with the end of the beam 29, energizing the hoist motor 69 to lower the hoisting shafts 166 and the track portion 27 supported thereby. 40 It is to be noted in this connection that the dogs 122 may freely pivot upward without tripping the limit switch 156 as the hoist control shaft 116 is lowered.

45 At the end of the desired leftward movement of the carriage W, limit switch 177, supported

from the rail 73 by the bracket 178, is tripped by an underportion of the carriage W and the traversing motor 65 is stopped. When the track portion 27 is lowered by operation of the hoist motor 69 to a position level with the incoming track T, the uppermost portion of the hoist control shaft 116 will have been lowered below the limit switch 179, secured to the mounting 184, thereby releasing the limit switch 179 and stopping the hoist motor 69.

Section V.—Operation

A summary of the operation of the present invention may be best presented in connection with the schematic plan of the electrical circuits, Fig. 9, which cooperate with the above described structure to effect its automatic operation. The motors 65 and 69 for the horizontal and vertical movements respectively of the track portion 27 are preferably conventional reversible electric motors connected with a 220-volt power source 182, for example. Upon closing the three normally open "left" relay switches 183, the motor 65 is caused to turn in one direction to move the traversing carriage W to the left. Upon opening switches 183 and closing the three normally open "right" relay switches 184, the motor 65 is reversed and the traversing carriage W is moved to the right.

Similarly closing the three normally open "up" relay switches 185 will cause operation of the hoist motor 69 to raise the track 27. Closing the three normally open "down" relay switches 186 and opening relay switches 185 will reverse the hoist motor 69 and lower the track 27. Overload circuit breakers or fuses 187 and 188 are in the circuits for the motor 65 and 69 respectively.

A 110-volt power source 189 may suitably be employed to power the control circuits through the three-position selector switch 192, which may be set at the "off" position 1 to disconnect the control circuit from its power source 189, the "automatic" position 2 to permit automatic operation of the electrical controls, or the "manual" position 3 to permit manual operation of the controls. It is to be noted that the normally open relay switch 193, in series with the selector switch 192, is operated from relay 194 in the circuit 195 for the pump motor, not shown, which supplies pressure to the pneumatic ram 158. Thus the control circuits of Fig. 9 cannot operate until the pneumatic pump circuit 195 has been previously closed.

In Fig. 9, selector switch 192 is set at position 2 for automatic operation of the control circuits. All limit switches and all relay switches are shown in their normal open or closed positions before a conveyor B is in the conveyor handling frame A and before electric current is supplied to the control circuits. We shall assume that no conveyor B is in the frame A, that an empty conveyor B is held at the end of the track T in readiness to ride on the track portion 27 under gravity upon being released by the walking beam escapement mechanism V, and that relay switch 193 is closed.

The escapement mechanism V is adapted to block any number of conveyors B from entering the frame A, but is actuated to release a single empty conveyor B to the frame A when solenoid 196 is energized. As may be observed from Fig. 9, solenoid 196 cannot be energized until all three switches 197, 171A, and 151A are closed. Relay switch 197 is normally closed unless relay 202 is energized. Since the energizing of relay 202 also closes relay switches 186, which operates

hoist motor 69 to lower the track 27, switch 197 will not prematurely close while the track 27 is still being lowered to the level of the incoming track T.

- 5 The normally open switch 171A is closed when limit switch 177 is tripped, i. e., when the carriage W has reached the extreme leftward extent of its travel in Fig. 4. Switch 151A is normally closed unless limit switch 151 is tripped, i. e., 10 when a conveyor B is already in position on track 27 and resting against the bumpers 125 at the lower left portion of the frame A, Fig. 4.

It is apparent that the danger of energizing the trip solenoid 196 and releasing an empty conveyor B from the track T into the hoist frame A is avoided until the track portion 27 has reached the proper downward and leftward limits of its movement, at which position the track portion 27 will be aligned with the end 20 of the incoming track T for receiving an empty conveyor B. Also even with the track 27 in its lower and leftward position, trip solenoid 196 cannot be energized if limit switch 151 is tripped by a conveyor B already in position within the 25 hoist frame A and adjacent the bumpers 125.

Upon satisfying the condition for closing switches 197, 171A, and 151A, solenoid 196 is energized and the walking beam escapement mechanism V is actuated to release an empty 30 conveyor B, which rolls from the track T on the rail portion 27 and against the bumpers 125 where it trips limit switch 151, opening switch 151A and also closing the circuit through the "right" relay 205. The opening of switch 151A 35 de-energizes the trip solenoid 196 so as to reset the walking beam escapement mechanism V to hold a subsequent empty conveyor B in readiness for release into the hoist frame A when the solenoid 196 is subsequently energized. The energizing of the "right" relay 205 closes the normally open relay switch 206 which by-passes limit switch 151, opens the normally closed relay switch 207 which is in series with the "left" relay 208, and closes the three normally open "right" relay switches 184 which cause the traversing motor 65 to move the carriage W and conveyor B now carried on the track 27 to the right in Fig. 4.

As the carriage W moves to the right, it rides off limit switch 177, and the conveyor B rides off limit switch 151. Thus limit switch 151 opens and the switch 151A associated therewith closes. Limit switch 177 closes and its associated switch 171A opens. Since relay switch 206 now bypasses limit switch 151, the opening of the latter does not interrupt the circuit through the "right" relay 205. Also the closing of limit switch 177 does not close the circuit through the "left" relay 208 because the normally closed relay switch 207 is now open.

The empty conveyor B continues to move to the right in Fig. 4 until it reaches the block loading position whereat the carriage W trips and opens the normally closed limit switch 153. The opening of limit switch 153 de-energizes the "right" relay 205, permitting the closing of the normally closed relay switch 207, the opening of the normally open relay switch 206, and the opening of the three normally open "right" relay switches 184, which latter action stops the conveyor B at its loading position.

With the conveyor B at its loading position, blocks H from the block-making machine C are carried by the chain conveyor I immediately 75 above the parallel shelf portions 25 which com-

prise the conveyor's top shelf J. The chain I preferably extends into the block receiving end of the conveyor B for essentially the entire length thereof and operates in synchronism with the machine C so that as each block H is completed, it is transferred while still on its pallet from the molding machine C to the chain conveyor I. The latter moves forward block by block to provide room for each succeeding block until the chain conveyor I is completely loaded as in Fig. 3.

When the foremost block H on the chain conveyor I reaches the rear of the conveyor B, it trips the normally open limit switch 155, energizing relay 213 which closes the normally open relay switch 214 in the circuit for the "up" relay 215. The energizing of the "up" relay 215 closes the normally open relay switch 216 in the by-pass circuit for the relay switch 214, opens the normally closed relay switch 217 in series with the "down" relay 202, and closes the three normally open "up" relay switches 185 in the circuit for the hoist motor 69, causing the latter to raise the conveyor B.

As the conveyor B is raised, the block H which has tripped limit switch 155 rides off that switch, opening the circuit through relay 213 and causing relay switch 214 to reopen. The opening of relay switch 214 does not de-energize the "up" relay 215 because relay switch 214 is now bypassed by the closed relay switch 216.

When conveyor B has been raised through an increment equal to the vertical spacing of the shelves J, the normally closed limit switch 156 is tripped and opened by the uppermost dog 122 on the hoist control shaft 116. Thus the circuit through the "up" relay 215 is broken, the three normally open "up" switches 185 open, and the conveyor B stops with its second shelf J from the top in the position formerly occupied by the uppermost shelf J prior to the hoisting operation, i. e., slightly below the upper surface of the conveyor chain I. The second shelf J from the top is then loaded by an essential repetition of the hoisting cycle, the conveyor chain I being first loaded, limit switch 155 being then tripped, conveyor B being then raised until the second dog 122 from the top on shaft 116 trips limit switch 156 and stops conveyor B with its third shelf in the loading position.

The loading procedure is repeated until each shelf J is loaded. In the present instance, the conveyor B shown has five shelves J and four dogs 122 so that the fifth hoisting operation continues until the rail 27 is aligned with the discharge rail K, at which position both limit switches 156 and 157 are tripped by the projection 124 provided by the lower portion of the shaft 116. The opening of limit switch 156 stops the upward movement of the conveyor B as heretofore described. The closing of the normally open limit switch 157 closes the circuit through the solenoid 218 which actuates the aforementioned air valve for the pneumatic ram 158 and causes extension of the plunger arm 164. The loaded conveyor B is thus pushed on the rail K by the flanged head 168 of the push-off rod 166. The conveyor B then rolls by gravity along the track K to the bridge crane M. The loaded conveyor B is then transported to the treating kilns O where the blocks H are steam cured or otherwise treated while still on the conveyor B, and then conveyed to the storage yards via the rails R. The empty conveyor B is returned from the storage yards via the rails S and T to the

walking beam V and is held in readiness to re-enter the frame A at the proper time.

As the conveyor B is pushed on the tramrail K, the arm 165 trips and closes the normally open limit switch 173. The closing of the switch 173 while limit switch 157 is also closed energizes the relay 219, which closes the normally open relay switch 222 in the by-pass circuit of limit switch 173, opens the normally closed relay switch 223 in series with the air valve solenoid 218 for ram 158, and closes the normally open relay switch 224 in the circuit for the "left" relay 208.

The de-energizing of air valve solenoid 218 upon the opening of switch 223 causes retraction of the plunger arm 164, permitting the normally open limit switch 173 to reopen, but relay 219 is not de-energized because limit switch 173 is by-passed by relay switch 222. Arm 164 remains retracted until limit switch 157 is again closed upon a subsequent operation of the loading cycle.

The energizing of the "left" relay 208 closes the normally open relay switch 225 in the by-pass circuit for relay switch 224, opens the normally closed relay switch 226 in the circuit for the "right" relay 205, and closes the three normally open "left" relay switches 183 in the circuit for the traversing motor 65. Thus the traversing motor 65 is energized to drive the carriage W to the left, releasing limit switch 157 to its normal open position.

The opening of limit switch 157 de-energizes relay 219, permitting the normally open relay switches 222 and 224 to reopen, and the normally closed relay switch 223 to close. The opening of relay switch 224 does not de-energize the "left" relay 208 since switch 224 is now by-passed by relay switch 225. Also, the closing of relay switch 223 does not re-energize the air valve solenoid 218 because limit switch 157 is now open.

Near the middle of the leftward movement of the carriage W, limit switch 175 is tripped by contact with beam 29 to close the circuit through the "down" relay 202. The energizing of the "down" relay 202 closes the normally open relay switch 227 in the by-pass circuit for the limit switch 175, opens the normally closed relay switch 197 in series with both the "up" relay 215 and trip solenoid 196, and closes the three normally open "down" relay switches 186 in the circuit for the hoist motor 69. Thus hoist motor 69 is energized to lower the hoisting shafts 66 and track 27. As the conveyor B moves down and rides off limit switch 175, the opening of that switch does not break the circuit through the "down" relay 202 since limit switch 175 is now by-passed by relay switch 227.

When the carriage W has moved to the desired leftward limit, the normally closed limit switch 177 in series with the now closed relay switch 225 is tripped by contact with the underportion of the carriage W to open the circuit through the "left" relay 208 and to stop the traversing motor 65, and also to close the associated switch 177A in the circuit for the trip solenoid 196. In addition to opening the three normally open "left" relay switches 183 in the circuit for the traversing motor 65, the de-energizing of relay 208 closes the normally closed relay switch 226 in the circuit for the "right" relay 205, and opens the normally open relay switch 225 in the by-pass circuit for relay switch 224.

When the downward movement of the track 27 has continued to the desired lower limit, the top of the hoist control shaft 116 will have been

lowered below the normally closed limit switch 179, releasing and opening that switch which is otherwise held closed by contact with the shaft 116, thereby de-energizing the "down" relay 202. The de-energizing of the "down" relay 202 opens the normally open relay switch 227 in the by-pass circuit for the limit switch 175, closes the normally closed relay switch 197 in series with the "up" relay 215 and the trip solenoid 196, and opens the three normally open "down" relay switches 186 which stop the hoist motor 69.

The track 27 having reached its desired lower and leftward limits in alignment with the incoming rail T, so that switches 197 and 177A are closed, and with switch 151A closed, there being no conveyor B in the frame A to trip limit switch 151, the trip coil 196 for the walking beam escapement mechanism V is energized and another empty conveyor B is permitted to roll from the track T to the track 27. Upon entry of the second empty conveyor B into the frame A, limit switch 151 is again tripped and the traversing motor 65 is energized to drive the carriage W to the right, thereby starting a repeat cycle of automatic operations as above described.

It is to be noted from Fig. 9 that when the selector switch 192 is moved to the manual position 3, the various hoisting and traversing operations may be effected by the four normally open jog switches, 228, 229, 232, and 233, which are associated respectively with the four normally closed jog switches 228A, 229A, 232A, and 233A, each of the four latter switches being opened when its associated jog switch is closed, thereby disconnecting the circuit controlled by the associated jog switch from automatic operation.

Upon closing jog switch 228, the circuit through the "up" relay 215 is closed and the hoist motor 69 is energized to raise track 27 as previously described if limit switch 156 is not open. Upon closing jog switch 229, the circuit through the "down" relay 202 is closed and the hoist motor 69 is energized to lower the track 27 as previously described if limit switch 179 is not open.

Upon closing the jog switch 232, the circuit through the "left" relay 208 is closed and the traversing motor 65 is energized to drive the carriage W to the left as previously described if limit switch 177 is not open. Upon closing the jog switch 233, the circuit through the "right" relay 205 is closed and the traversing motor is energized to drive the carriage W to the right as described above if limit switch 153 is not open.

I claim:

1. In a material handling system adapted for use with a block making machine and comprising a plurality of tram conveyors, a tram rail circuit starting at a loading point adjacent the discharge end of the block making machine and leading therefrom through a curing kiln and then returning to the starting point; tram conveyor handling means including a frame; a movable rail portion adapted to receive an empty tram conveyor at the rear of the said frame and move said empty tram conveyor transversely to a loading position at the front of said frame; screw-threaded hoisting shaft means affixed rigidly at one end to the top of said rail portion; a transversely movable carrier member actuated by an electric traversing motor and located atop said frame, said carrier member having in-

ternally screw-threaded rotatable bushings which are immovable in a vertical direction, said bushings being adapted for rotation by an electric hoisting motor to move said hoisting shaft means vertically relative to said carrier member and bushings when said bushings are rotated; a hoist control shaft disposed adjacent said hoisting shaft means and movable therewith, said hoist control shaft having vertically spaced dogs disposed thereon and a projection disposed below said spaced dogs, said spaced dogs being adapted to trip a limit switch to stop vertical movement of said hoisting shaft means at predetermined increments during loading of the tram conveyor, and said projection being adapted to trip a limit switch to stop vertical movement of said hoisting shaft means at the upward limit of travel and at the same time actuate a push-off mechanism to move a loaded conveyor onto a tram rail leading to the curing kilns; means for returning said push-off mechanism to its original position; means for actuating the traversing motor to return the said movable rail portion to the rear part of the frame; and means to actuate the hoisting motor and lower the rail portion to the tram conveyor receiving position.

2. A device as claimed in claim 1 and further characterized in that the said vertically spaced dogs on said hoist control shaft are pivotally disposed in slots with the pivot point of each dog lying closer to the bottom of the respective slot than the top so that the dogs are held in an extended position against the bottom of the slot when the said hoist control shaft moves upward and are pivotally moved into the said slots upon encountering any obstruction when the hoist control shaft moves downward.

3. Material handling device adapted to load and handle an empty material transporting unit, comprising a frame adapted to receive said material transporting unit, a receiving member disposed in said frame and adapted to engage said transporting unit, screw-threaded hoisting means affixed rigidly at one end to the top of said receiving member, a carrier member disposed atop said frame, internally screw-threaded rotatable bushings mounted on said carrier member and secured against vertical movement, an electric hoisting motor adapted to rotate said bushings and move said hoisting means vertically relative to said carrier member and bushings, a hoist control shaft disposed adjacent said hoisting means and movable therewith, said hoist control shaft having vertically spaced dogs disposed thereon and a projection disposed below said spaced dogs, a limit switch disposed on said carrier member and electrically connected with said hoisting motor, said spaced dogs being adapted to trip said limit switch to stop vertical movement of said hoisting means at predetermined increments during loading of the material transporting unit, and said projection being adapted to trip said limit switch to stop vertical movement of said hoisting means at the upward limit of travel, and means to actuate said hoisting motor and lower said receiving member to its initial position.

4. A device as claimed in claim 3 and further characterized in that the said vertically spaced dogs on said hoist control shaft are pivotally disposed in slots with the pivot pin of each dog lying closer to the bottom of the respective slots than the top so that the dogs are held in an extended position against the bottom of the slots

17

when the said hoist control shaft moves upward and are pivotally moved into the said slots upon encountering any obstruction when the hoist control shaft moves downward.
